UNITED STATES PATENT OFFICE.

JOSEPH H. HUBBELL, OF DAYTON, OHIO.

HYDRAULIC PUMP.

SPECIFICATION forming part of Letters Patent No. 331,711, dated December 1, 1885.

Application filed June 5, 1885. Serial No. 167,757. (No model.)

To all whom it may concern:

Be it known that I, JOSEPH H. HUBBELL, a resident of Dayton, in the county of Montgomery and State of Ohio, have invented certain new and useful Improvements in Hydraulic Pumps, of which the following is a specification.

My invention relates to improvements in hydraulic pumps.

10 One of the objects of my invention is to provide automatic means for stopping the pumping when the desired amount of pressure has been obtained.

Another object of my invention is to combine a series of high with one or more low pressure pumps, so that the low and high pressure pumps will successively contribute to obtaining the power, and each be automatically released from labor when it has produced 20 its respective limit of pressure or power.

Another object of my invention is to so combine a series of pumps that one or more of the high-pressure pumps can be worked at the same time and in conjunction with the low-pressure pumps which work in conjunction with one or more of the high-pressure pumps. By employing the pumps hereinafter described I am enabled to avoid all danger of bursting the pumps by supplying tripping-30 pistons and connections to automatically stop the pumping operations as soon as the desired pressure is obtained, and which automatically commence labor if the pressure in the force-main should fall below the maximum 35 point.

The various features and other objects of my invention will be fully set forth in the description of the accompanying drawings, forming a part of this specification, in which—

40 Figure 1 is a side elevation of my improved pump; Fig. 2, a top plan view of the series of pumps. Fig. 3 is a central longitudinal section of one of the low-pressure pumps. Fig. 4 is a central vertical longitudinal section of the other low-pressure pump. Fig. 45 5 is a central longitudinal section of one of the series of high-pressure pumps. Fig. 6 is a section of the same on line $x-x$, Fig. 5. Fig. 7 is a similar section on line $y-y$, Fig. 50 5. Fig. 8 is a section on line $z-z$, Fig. 5. Fig. 9 is a partial plan view showing the connection of the low to the high press-

ure pumps. Fig. 10 is a section showing the manner of connecting the passages between the different cylinders. Fig. 11 is a diagram 55 showing the position of cranks. Fig. 12 is a side elevation of my improved cross-head. Fig. 13 is a longitudinal vertical section of the same; and Fig. 14, a section on line $a-b$, Fig. 13.

60 A A A A represent the frame-work of the machine, on which the series of pumps are placed.

B represents the main driving-pulley.

b represents driving-gear on the driving-shaft B' , and b' represents driving-gear on the crank-shaft.

1 2 3 4 5 6 7 represent a series of cranks set at different angles, as shown in diagram Fig. 11, for driving the series of pumps C D E F 70 G H I. Those pumps are preferably each made of a block of metal cast integral and cored and finished, with ports, passages, and chambers, as hereinafter described. They are placed parallel with each other upon the main 75 frame of the machine in proper plane to be in line with the cranks and cross-heads. The two outside pumps C and I are designed for low-pressure pumps. Each is provided with a passage or opening, K, pierced clear through 80 the block of the pump. Each of the series of high-pressure pumps is provided also with a similar passage, K, bored in like manner, and these several passages of the different pumps are connected to each other by bushing-pipes 8, as 85 shown in Fig. 10, so as to form a continuous passage passing clear through the series, so that the supply-pipes J J', at either side supply all of the pumps with the fluid operated upon by the pump-pistons to produce the power. 90

9 represents the suction-valve on each of these low and high pressure pumps.

10 represents the low-pressure pistons, and 11 the high-pressure pistons. The low-pressure pistons 10 are preferably of ten times the 95 area of the high-pressure pistons 11. Oil is preferably employed in the operation of the pumps; but any other suitable fluid may be used.

12 represents the check-valves in the passage 100 above the pistons leading to the pressure-pipes.

In the ordinary operation of the low-pressure pump C, the oil is drawn up through valve

9 into passage a , and forced by the piston through passage a' , raising check-valve 12, through passage a'' , into passage L, which passage is common to all of the pumps, as shown 5 in plan, Fig. 9, the several blocks being connected by bushings l' .

13 represents a low-pressure safety-valve opening out from passage a'' , and M represents a weighted tripping-piston, which governs the 10 operation of the low-pressure pump in the following manner, as shown in Fig. 1.

d represents the weighted arm holding down the piston M.

d' represents the weight.

15 14 represents a link connecting arm d to lever 15, which is hinged to stem or piston 16, which works in the stuffing-box 17, passing vertically through and up into or against the suction-valve 9, as shown in Figs. 3, 4, 5. The 20 weight d' is adjusted on lever D, to limit the amount of pressure produced by the pumps C and I. When the pressure in passage L is greater than the limit at which the weight d' is adjusted to hold, the piston M will rise and 25 lift the arm d , and with it link 14, arm 15, and piston 16, the raising of which piston holds the suction-valve 9 up off its seat, and stops the work of the pump-piston 10. Each of 30 the pumps C and I is provided with similar regulating or tripping pistons, M, and automatic lifting apparatus for holding up the foot-valve 9.

As the passage L is common to the pumps C and I, the same pressure upon the pump-piston will operate regulating-piston M in a uniform manner, which are weighted, say, ordinarily to a limit of four hundred pounds' pressure to the square inch. It follows, then, that when that limit is reached, if the piston 10 is 40 traveling outward, regulating-piston M will be raised, and through it valve 9 kept from seating, and thus the operation of the pump will be stopped; but if the piston 10 be traveling inward regulating-piston M cannot rise 45 against the inward stroke of piston 10 to operate piston-rod 16, connected to the weighted arm d , and hence will not raise the valve 9, because the pressure is balanced between piston M and valve 9. Upon the next outstroke, however, of the piston, the pressure upon valve 9 50 will be relieved, and it will be caused to rise. At the same time valve M will be raised, and be kept in such raised position so long as the pressure in the pumps exceeds the weight 55 upon the lever of the valve, and by the connections with valve 9 this valve will be kept in its raised condition likewise, and the operation of the pump be stopped.

To prevent the generation of an undue 60 amount of pressure by the inward stroke of piston 10, I provide a safety-valve, 13, connecting the said passage L, which is weighted, say, at a pressure of ten or more pounds greater than the weight of regulating-piston 65 M, so that the pressure cannot, by the return-stroke of piston 10, be increased above four hundred and ten pounds to the square inch

without lifting the valve 13, to relieve the excess of pressure during this portion of the stroke.

70 N represents a passage running through the pumps D E F G H I, and connecting by port N' with the high-pressure safety-valve O, which is preferably placed on pump I. This high-pressure safety-valve works only in 75 connection with the operation of the high-pressure pumps, which are all constructed alike in the following manner.

9 represents the suction-valves; 11, the piston; 12, the check-valve in the passage e, opening into passage e. 17 represents the check-valve in passage e for closing passage L. Passage e is sufficiently large around check-valve 17 to be unobstructed by it when raised off its seat.

80 P represents the pressure-pipe leading to the piston-chamber of the press. Each high-pressure pump is provided with independent pipes P, so that each one may operate upon a different press-piston in unison with or independent of each other.

85 R represents a high-pressure regulating or tripping piston. It is provided with a weighted arm, f, link g', and plunger-rod 16, seating against the foot of valve 9, and acting 90 in the same manner, as before explained, of the low-pressure regulating-piston and connections. Arm f is weighted, so as to limit the pressure of the piston 11 to four thousand pounds per square inch, so that when the 100 pressure rises to this amount and increases above it it will raise the piston R, and with it the connections to hold the foot-valve 9 off its seat, and stop the operation of the pump on the outward stroke of the piston.

105 In order to prevent an undue excess of pressure, caused by the return-stroke of the piston 11, after the pressure has reached four thousand, I provide a high-pressure safety-valve, which connects with passage e, through check-valve 19, leading into passage N, which is sufficiently large to prevent check-valve 19 from obstructing the passage when lifted. As the passage N is common to the pumps D E F G H, passing through pump I, and communicating, 110 through passage N', with the high-pressure safety-valve O, which is weighted, say, to ten or more pounds above the regulating-piston R, so that on the return-stroke of piston 11 the high-pressure valve O will rise, to relieve 115 the accumulation of pressure above four thousand on this return-stroke on any one of the series of high-pressure pumps, and on the next outstroke of such piston 11 the regulating-piston R will rise, and by its connection hold suction-valve 9 off its seat, stopping the pumping 120 of piston 11.

125 20 represents stuffing-boxes, which are constructed in the ordinary manner, to fit and hold the different valves and pistons working 130 therein. The several pump-blocks C D E F G H I are secured together by through-bolts 22 23 24 25 26.

The pumps are operated in the following

manner: The low-pressure pumps are limited in work to, say, about four hundred pounds pressure to the square inch by regulating the weight d' of the regulating-piston M. The 5 safety-valve 13 is weighted a little higher. Valve S in the pipe P, leading to the piston-chamber of the press, is opened, when the low-pressure pumps will commence supplying this piston-chamber with fluid, passing through 10 valve 9, passages a , a' , and L, through check-valve 17 and passage e, into any one of the pipes P, which are open to supply the piston-chamber of its press. As soon as the pressure is raised to four hundred pounds, or the amount 15 at which the regulating-piston M is weighted, it will rise on the pumps C and I, and lift the check-valve, and stop the supply of oil or the fluid being pumped into the piston-chamber of the press. The high-pressure pump connected 20 to the press through pipe P, that is opened, is likewise at work at the same time with the low-pressure pump; but the object of the low-pressure pumps is to raise the pressure quickly to their limit, and then allow the 25 smaller and high-pressure pumps to complete the work more slowly. The high-pressure pump continues its work until its limit is reached, when, as before described, the regulating-piston R will rise and, with the connecting-link, lift the plunger 16 and suction-valve 9, and stop the pumping of piston 11. All 30 the pistons keep running, and their work is relieved by the holding of its suction-valve 9 up off its seat. Should, now, the pressure 35 in the pipe P fall below the limit to which the piston R is weighted, the lever f would immediately drop, closing the piston R down onto its seat, and the suction-valve 9 will commence operating. Piston 11 will pump the fluid into 40 the pipe P until the pressure is again raised to the limit. Thus these several high-pressure pumps will work individually its particular press, and keep the press at the desired limit of power automatically, avoiding the care and 45 watchfulness of the attendant to maintain the pressure.

By employing the regulating-piston in conjunction with the safety-valve herein set forth I have a double safeguard against running up 50 the pressure high enough to burst the piston-chamber of the press, which accident is of frequent occurrence in the other form of pumps which do not employ the combined safety and regulating devices.

55 h represents the pitman plunger-heads of the pumps.

T represents a wrist-block for the cross-heads, to which they are connected.

i represents a recess. It is provided with 60 screw-threads, into which the screw-threaded plunger-head k taps.

U represents a detachable section of the wrist T, which is connected to wrist-block T, set-screw r engaging against shoulder t of the 65 incline.

m represents packing-plates, which are pref-

erably composed of a number of strips of steel; n, a set-screw passing through said packing-strips and tapping into the section U.

v represents a wrist-pin hinging the pitman 70 h to the wrist-block. Any wear of the joint-connections may be taken up by means of these packing-strips m and by means of the set-screw r .

Another advantage of employing the detachable wrist-section U, held by the inclined set-screw r , is that it may be more easily taken apart and put together than the wrist-connections hitherto employed for this purpose. 75 80

I claim—

1. The combination of a low-pressure and a high-pressure pump having in common an inlet-pipe, K, and an exit-pipe, L, and each formed with a piston-chamber communicating with the said inlet-pipe, a suction-valve controlling the communication between said pipe and chamber, a piston working in its chamber, a passage communicating with said exit-pipe, a passage connecting said passage 90 and piston-chamber, a check-valve controlling said connecting-passage, a weighted regulating-piston working in the passage communicating with the exit-pipe, and a system of levers connecting said weighted piston and 95 the suction-valve, the high-pressure pump being also provided with a valve, 17, at the union of the exit-pipe and its communicating-passage, and a pressure-pipe, P, substantially as and for the purposes described. 100

2. The combination of a low-pressure and a high-pressure pump having in common an inlet-pipe, K, and an exit-pipe, L, and each formed with a piston-chamber communicating with said inlet-pipe, a suction-valve controlling the communication between said pipe and chamber, a passage communicating with said exit-pipe, a passage connecting said passage and piston-chamber, a check-valve controlling said connecting-passage, a weighted regulating-piston working in the passage communicating with the exit-pipe, and a system of levers connecting said weighted piston and the suction-valve, the high-pressure pump being also provided with a passage, N, communicating 115 with the regulating-piston passage, a high-pressure safety-valve, O, connected therewith, and a check-valve, 19, controlling the communication between the regulating-piston passage and passage N, substantially as and for the purposes described. 120

3. The combination of a series of low-pressure and a series of high-pressure pumps having in common an inlet-pipe and an exit-pipe, each pump having an independent piston and valve-controlled passages connecting the inlet and exit pipes, a suction-valve, and a weighted regulating-piston connected by a system of levers with the suction-valve, the low-pressure pumps being each further provided with a safety-valve so weighted above 125 the regulating-pistons, and the high-pressure 130

pumps having a safety-valve common to all of them, substantially as and for the purposes described.

4. The combination of a series of high-pressure pumps connected with one or more low-pressure pumps by a continuous passage, each having independent regulating-pistons for controlling the work, and a single safety-valve common to all the high-pressure pumps, for preventing undue pressure upon the pump-pistons, substantially as specified.

5. The cross-head connection consisting of the block T, detachable section u, packing-strips m, and set-screw r, for connecting the pitman h with the pump-piston, substantially as specified. 15

In testimony whereof I have hereunto set my hand.

JOSEPH H. HUBBELL.
